UNITED STATES PATENT OFFICE.

JEFFERSON C. SHANNON, OF GREENVILLE, MISSISSIPPI.

BODY-PROTECTOR.

1,302,980.

Specification of Letters Patent.

Patented May 6, 1919.

Application filed July 6, 1918. Serial No. 243,593.

To all whom it may concern:

Be it known that I, JEFFERSON C. SHANNON, a citizen of the United States, residing at Greenville, in the county of Washington 5 and State of Mississippi, have invented new and useful Improvements in Body-Protectors, of which the following is a specification.

This invention relates to protectors, particularly to body protectors for use by undertakers, and has for its object the provision of a protector adapted to be engaged partially beneath and around a body being embalmed whereby the body, clothing, 15 sheets, carpets and the like will be protected from injury or damage resulting from any accidental spilling of blood or embalming fluid.

An important object is the provision of a 20 protector of this character which is so formed as to provide a pocket for catching and holding any blood or chemicals which might be spilled during the process of embalming the pocket being so formed and so 25 located in respect to the main portion of the protector as to have the maximum efficiency in preventing the spilling of any fluids.

Another object is the provision of a protector of this character embodying two flaps, 30 one of which is designed to be disposed beneath the body and the other of which is so formed as to be placed over a portion of the body in close engagement with the arm pit whereby the body, clothing and adjacent 35 objects will be effectively protected during the customary operation.

Another object is the provision of a device of this character having a pocket portion which is maintained in proper shape by 40 a metallic frame formed of a plurality of rods, the rods being so arranged and connected that they may be folded in respect to one another so that the entire device may be folded about the rods into a very small compact package or parcel for convenience in transportation and storage.

Still another object is the provision of a device of this character which will not only be efficient in its action, but which will also 45 be extremely simple and inexpensive in manufacture and use, easily applied, and a general improvement of the art.

With the above and other objects and advantages in view, the invention consists in 50 the details of construction to be hereinafter more fully described and claimed and illus-

trated in the accompanying drawings in which:—

Figure 1 is a plan view of the device in its extended position applied to a body. 60

Fig. 2 is a bottom plan view showing in full lines the rods extended and in dotted lines the rods folded.

Fig. 3 is a detail sectional view illustrating the pocket construction, and 65

Fig. 4 is a view showing the device completely folded.

Referring more particularly to the drawing the numeral 10 designates a sheet of material which is cut to provide the side flaps 70 11 and having its edges at one end turned over and stitched along the lines 12 to provide a bead 13 within which is disposed a U-shaped frame 14. The frame 14 has its arms formed in jointed sections 15 for a 75 purpose to be hereinafter described. The portion of the sheet 10 within the confines of the frame 14 is designed to form a shallow receptacle or pocket the utility of which will hereinafter become apparent. 80

Disposed upon the sheet 10 and secured thereto by rows of stitching 16 and 17, is a second sheet 18 which is of considerably greater length than the sheet 10 so as to extend therebeyond in one direction, and which 85 has its other end terminating adjacent the pocket defined by the frame 14.

The width of the sheet 18 is such that it extends over one of the flaps 11 of the sheet 10 while the other flap is not covered 90 thereby. At one edge, the sheet 18 is provided with a curved cut out portion 19 of a size to be conveniently engaged about the shoulder of a body.

In the use of the device, the sheet 10 is 95 placed upon some convenient support, preferably a cooling board A, with the rods of the frame 14 disposed lowermost. The sheet is so positioned in respect to the cooling board or other support, that the pocket 100 defined by the frame 14 will extend beyond the edge of the board or other support. The operator then grasps the free end of the sheet 18 and swings it back upon its line of stitching 16 until the sheet 18 is in a non-obstructing position in respect to the portion of the sheet 10 lying between the lines of stitching 16 and its free end. The body 105 is then laid upon the sheet 10, after which the sheet 18 is drawn over the body with 110 the cut out portion 19 engaging the arm pits. It is understood of course that when the

body is initially laid upon the sheet 10, its position should be so judged that the arm pit will be in proper position to be engaged by the cut out portion 19. The weight of 5 the body resting upon the jointed sections 15 of the frame 14 will hold the frame 14 in proper position so that there will be no displacement of the pocket defined thereby. The proper positioning of the protector in 10 respect to the body is clearly shown in Fig. 1 of the drawing and an inspection of this figure will reveal the fact that the protector allows one arm to be exposed so that the embalmers may perform their work conveniently. It will be noted that the exposed 15 arm will be adjacent the pocket defined by the frame 14 so that any blood exuding from the incision in the arm or any embalming fluid spilled will be caught by the 20 pocket. It will be observed that the device will thus effectively prevent damage to the body, clothing, sheets, carpets or other adjacent objects owing to any spilling of fluid.

Fig. 2 shows a bottom plan view of the 25 parts in their normal or active positions. When the use of the device is no longer desired, the jointed sections 15 of the frame 14 are moved from the position shown in Fig. 2 by full lines into the position shown by 30 dotted lines which illustrates them swung one upon the other and extending transversely of the sheet 10. The flaps 11 are then folded into the sheet 10 and the projecting edge of the sheet 18 folded onto the adjacent folding flap 11. When the parts are 35 so arranged, the operator need only grasp the frame 14 by one corner and turn it over and over upon the super-posed sheets 18 and 10. The device may thus be rolled up 40 into a small bundle as shown in Fig. 4 with the frame 14 disposed within the folded sheets.

From the foregoing description and a 45 study of the drawings it will be apparent that I have thus provided a protector for the purpose described which will be ex-

tremely simple in use, efficient in action, durable in service and which will moreover be inexpensive in manufacture.

While I have shown and described the 50 preferred embodiment of my invention it will of course be understood that I reserve the right to make such changes in the form, construction and arrangement of parts as will not depart from the spirit of the invention nor the scope of the subjoined claims. 55

Having described my invention I claim:—

1. An undertaker's body protector, comprising a substantially rectangular sheet of material adapted for disposition upon the 60 cooling board beneath a body disposed thereon, an open sided rectangular frame secured at one end of said sheet of material and defining a pocket adapted to project beyond the edge of a cooling board, and a 65 second sheet of material of substantially rectangular formation secured upon said first named sheet at a point spaced from the open side of said frame and disposable over the torso of a body laid upon the first named 70 sheet, said second named sheet being provided adjacent one secured corner with an arm pit engaging portion.

2. An undertaker's body protector comprising a sheet of material disposable upon 75 a cooling board and adapted to receive thereon a body, an open sided rectangular frame secured at one end of said sheet of material and forming a catch basin 80 adapted to overhang the edge of the cooling board, extension rods pivotally connected with the side arms of said frame and disposed beneath said sheet of material and the body disposed thereon, whereby said basin will project in a horizontal position, and a 85 second sheet of material secured upon said first named sheet adjacent the open side of said frame and engageable over the torso of a body disposed upon said first named sheet.

In testimony whereof I affix my signature. 90

JEFFERSON C. SHANNON.
